US00D894227S

(12) **United States Design Patent** (10) **Patent No.:** **US D894,227 S**
Kane et al. (45) **Date of Patent:** **** Aug. 25, 2020**

(54) **DISPLAY SCREEN OR PORTION THEREOF WITH A GRAPHICAL USER INTERFACE**

(71) Applicant: **Beijing Microlive Vision Technology Co., Ltd.**, Beijing (CN)

(72) Inventors: **Travis Kane**, Los Angeles, CA (US); **Hui Sun**, Shanghai (CN); **Michael Martinho**, Beverly Hills, CA (US); **Raffi Baghoomian**, Los Angeles, CA (US)

(73) Assignee: **Beijing Microlive Vision Technology Co., Ltd.**, Beijing (CN)

(**) Term: **15 Years**

(21) Appl. No.: **29/673,703**

(22) Filed: **Dec. 17, 2018**

Related U.S. Application Data

(63) Continuation of application No. 29/651,478, filed on Aug. 17, 2018, now Pat. No. Des. 870,140.

(57) **CLAIM**

We claim the ornamental design for a display screen or portion thereof with a graphical user interface, as shown and described.

DESCRIPTION

The FIGURE is a front view of a display screen or portion thereof with a graphical user interface showing our new design.

The broken lines shown in the FIGURE represent portions of the display screen or portion thereof with a graphical user interface that form no part of the claimed design.

1 Claim, 1 Drawing Sheet
